CLAIM

The ornamental design for a curved body of cheese made of longhorn-shaped slices of cheese, as shown and described.

DESCRIPTION

FIG. 1 is a perspective view of a curved body of cheese made of longhorn-shaped slices of cheese showing my new design, the broken away area indicating indeterminate height of the stack;

FIG. 2 is a front elevational view thereof;

FIG. 3 is a first side elevational view thereof;

FIG. 4 is a rear elevational view thereof;

FIG. 5 is a second side elevational view thereof;

FIG. 6 is a top plan view thereof; and,

FIG. 7 is a bottom plan view thereof.
